UNITED STATES PATENT OFFICE

CHARLES C. CALL, OF HAYDEN, INDIANA.

HAIR-STRAIGHTENER.

No. 846,183.

Specification of Letters Patent.

Patented March 5, 1907.

Application filed April 30, 1906. Serial No. 314,521.

To all whom it may concern:

Be it known that I, CHARLES C. CALL, a citizen of the United States, residing at Hayden, in the county of Jennings and State of Indiana, have invented certain new and useful Improvements in Hair-Straighteners, of which the following is a specification.

This invention relates to new and useful improvements in methods of and devices for straightening curly "kinky" hair.

The invention especially contemplates novel means for attaining this object in which the hair is subjected to a strain simultaneously in different directions.

In connection with the above general object the invention specifically comprises interfitting irons adapted to be heated and to grasp the hair therebetween.

A further object of the invention is the provision of handles by which said irons are carried and which in the operative position of the device are offset at an angle of approximately forty-five degrees from the irons.

The detailed construction will appear in the course of the following description, in which reference is had to the accompanying drawings, forming a part of this specification, like numerals designating like parts

throughout the several views, wherein—

Figure 1 is a perspective view illustrating the hair-straightener constructed in accordance with my invention, and Fig. 2 is a side elevation showing the irons spread apart.

In the practical embodiment of my invention I employ a pair of irons 1 and 2. These irons are each provided throughout their lineal extent with coextensive transverse corrugations 3, designed to interfit one another in the confronting relation of the irons in practical use. The irons 1 and 2 are provided at their ends with rearwardly-extending shanks 4, which intersect one another and are pivotally united at their junction by

a screw 5. Handles 6 are provided at the ends of the shanks 4, by which the irons 1 and 2 are manipulated.

With reference to Fig. 2 it will be noted by the dot-and-dash line 7 that the longitudinal axis of the handles 6 lies at an angle of approximately forty-five degrees to the plane of the irons 2 in their operative position.

In practical use the irons 1 and 2 are heated in any desired manner and are then closed with the corrugations 3 extending in a vertical direction upon a mass of hair. In this operation the device is manipulated by grasping the handles 6. The irons 1 and 2, with the corrugations 3 in their interfitting position, are moved substantially in a vertical plane and at the same time at a slight angle to a perpendicular line. This mode of use causes a strain to be imparted to the hair in the direction of relative movement of the irons 1 and 2 and in the direction of angular displacement of said irons from the vertical direction of the corrugations 3, between which the hair is clamped. The result of the above method of use is that the hair being subjected to heat and to a pulling strain is released from the irons 1 and 2 perfectly straight.

It is obvious that various changes may be made in the invention without departing from the spirit and scope thereof as defined in the appended claims.

Having fully described my invention, I claim—

1. A hair-straightener, comprising a pair of solid plates with transverse interfitting teeth of triangular cross-section and a pair of crossed handles secured thereto.

2. A hair-straightener, comprising a pair of solid plates with transverse interfitting teeth of triangular cross-section and a pair of crossed handles secured thereto and extending therefrom at an angle to the plane as well as to the longitudinal axis of said plates.

In testimony whereof I affix my signature in presence of two witnesses.

CHARLES C. CALL.
